(57) CLAIM

The ornamental design for a plumbing fixture, as shown and described.

DESCRIPTION

FIG. 1 is a right, top, front perspective view of a plumbing fixture embodying our new design;

FIG. 2 is a front elevational view thereof;

FIG. 3 is a top plan view thereof;

FIG. 4 is a left side elevational view thereof;

FIG. 5 is a right side elevational view thereof; and,

FIG. 6 is a rear elevational view thereof.

The broken line representations in the figures are for the purpose of illustration only, and form no part of the claimed design.

In a preferred embodiment, the nature of this product is a plumbing fixture in the form of a wall-mounted toilet.
